UNITED STATES PATENT OFFICE

168,161

COMPARTMENTED DISPLAY DISH

Thomas W. Kyte, New York, N. Y.

Application August 2, 1950, Serial No. 11,555

Term of patent 3½ years

(Cl. D44—8)

To all whom it may concern:

Be it known that I, Thomas W. Kyte, a citizen of the United States, residing in New York city, county and State of New York, have invented a new, original, and ornamental Design for a Compartmented Display Dish, of which the following is a specification, reference being had to the accompanying drawing, forming part thereof, and in which:

The dominant features of my design reside in compartments of the dish comprised of a central, double-walled, square compartment from the corners of which radiate single-walled partitions forming four other compartments, as shown.

I claim:

The ornamental design for a compartmented display dish, as shown and described.

THOMAS W. KYTE.
